UNITED STATES PATENT OFFICE

ATAULFO FERNANDEZ Y FERNANDEZ, OF HAVANA, CUBA

FUEL BURNER

Application filed September 3, 1929, Serial No. 390,174, and in Cuba September 18, 1928.

This invention relates to a fuel burner; and more particularly, to a burner of the type utilizing vaporized fuel.

The principal object is to provide a burner which will do away with the usual wick and at the same time will have a preheating chamber that will greatly facilitate the vaporizing of the fuel. Various means have been designed for positively conveying either the fuel or vapor to a burner portion, but it is believed that the use of loose wires in the manner arranged in my construction is far superior to any of the other devices.

Another object is to provide means for controlling the mixing of air with the vaporized fuel so as to obtain the maximum of heat from the fuel used.

Other objects will be shown in the specification and drawings, made a part of this application.

In the drawings:

Figure 1 is a perspective of the entire burner;

Figure 2 is a vertical section taken on the line 2—2 of Figure 3;

Figure 3 is a top plan of the burner showing the wires in position;

Figure 4 is a perspective of the inner tube removed from the burner jacket.

Figure 5 is a perspective of the muff removed from the inner tube; and

Figure 6 is a cross section taken on line 6—6 of Figure 2.

Referring to the drawings, in which like parts are designated by similar numerals:

Numerals 1 designates a burner having an outer jacket 2, and a base 3 in the form of a fuel reservoir 4. A fuel inlet pipe 5 leads into the reservoir 4. Adjacent the top edge 6 of the jacket 2, and encircling the same, is a trough or well 7 to receive a preheating fuel 8. Extending up through the burner 1 is an inner tube 9, having a neck 10, containing openings 11. Around the bottom portion 12 of the inner tube 9 are elongated slots 13. Encircling the bottom portion 12 is a muff 14 having elongated slots 15, which coincide with the slots 13 in the bottom portion 12 of the inner tube 9. Extending into the reservoir 4 are a number of loose wires 16, which

act as a wick and extend above the well or trough 7 to the top of the inner tube 9. A plate 17 closes the inner tube 9, with the exception of air vents 18.

As actually operated, the reservoir 4 will be filled with a vaporous fuel from the pipe 5. A small quantity of fuel 8 will be placed in the trough or well 7 and ignited. The ignited fuel will heat the upper ends of wires 16, and by way of conduction, the entire length of wires will be heated, thus heating the fuel in the reservoir 4 and causing the same to vaporize. The vapor will ascend along the wires 16 and will become ignited at the upper ends of the wires adjacent the well or trough 7. As soon as the wires 16 have become sufficiently heated, and the vapor ignited, the trough or well 7 will no longer be needed, and the fuel therein will be allowed to burn out, only enough being placed therein to serve the function of preheating.

The muff 14 controls the flow of air through the inner tube 9, which has a direct bearing on the type of flame produced—much in the same manner as that produced in a "Bunsen" burner. The air will pass from the inner tube 9 out through the openings 11 in the neck 10 and mix with the vaporized fuel. A slight turn of the muff 14 will open or close the elongated slots 13 in the inner tube 9.

The use of loose wires 16 serves the double purpose of vaporizing the fuel in the reservoir 4 and providing interstices to convey the vaporized fuel to the point of ignition. This produces a very efficient and simple structure, whereby a very hot flame will be produced.

I do not intend to limit myself to the particular structure shown in my application, as other means may be employed without departing from the scope of my invention.

What I claim is:

1. A burner comprising a fuel reservoir; an outer tube extending from the reservoir; an inner tube extending through the outer tube, providing an air passage; wires filling the space between the outer and inner tubes and reaching into the reservoir; and means intermediate the ends of the outer tube for di- 100

verting air from the inner tube into the interstices between the wires.

2. A burner comprising a fuel reservoir; a vapor tube extending from the reservoir; an air tube extending through the vapor tube, having an outlet within the vapor tube; heat conducting wires filling the space between the vapor tube and the air tube and reaching into the reservoir to vaporize liquid fuel; and a head adapted to divert air passing through the air tube into the interstices between the wires.

3. The same structure as claim 2 and a priming fuel cup for heating the wires to start vaporization of fuel in the reservoir.

4. A burner comprising a fuel reservoir; a vapor tube extending upwardly from the reservoir; an air tube extending through the vapor tube, having a side outlet below the top of the vapor tube; a bundle of loose parallel wires filling the space between the vapor tube and air tube, formed of a good heat conducting metal for conducting heat down to vaporize liquid fuel in the reservoir and providing interstices between the wires for the fuel vapor to pass up to a combustion zone above the vapor tube; and a perforated head in the air tube adapted to allow portions of air rising through the air tube to pass directly to the combustion zone and to divert other portions through the side outlet into the interstices between the wires.

5. The same structure as claim 4 and a valved air inlet at the bottom of the air tube.

35 6. A burner comprising a fuel reservoir; a vapor tube extending from the reservoir; an air tube extending through the vapor tube; a neck forming a part of the air tube having an air outlet and dividing the air tube into a lower cylinder and an upper cylinder; wires filling the space between the vapor tube and air tube; a head forming the top of the upper cylinder, having an air outlet; and a head connected to the neck and forming the bottom of the upper cylinder, adapted to divert air from the neck outlet into the interstices between the wires.

In testimony whereof I affix my signature.

ATAULFO FERNANDEZ y FERNANDEZ.
